UNITED STATES PATENT OFFICE.

ISAAC N. JARSON AND FREDERICK W. MARTIN, OF CINCINNATI, OHIO.

DESIGN FOR A BOTTLE.

Application filed August 25, 1926. Serial No. 18,866. Term of patent 14 years.

To all whom it may concern:

Be it known that ISAAC N. JARSON and FREDERICK W. MARTIN, both citizens of the United States, and residents of Cincinnati, in the county of Hamilton and State of Ohio, have invented a new, original, and ornamental Design for a Bottle, of which the following is a specification, reference being made to the accompanying drawing, forming part hereof.

The figure is an elevational view of a bottle, showing our new design.

We claim:

The ornamental design for a bottle, as shown.

ISAAC N. JARSON.
FREDERICK W. MARTIN.
